LAPPING MACHINE

Herbert S. Indge, Westboro, Mass., assignor to
Norton Company, Worcester, Mass., a corpora-
tion of Massachusetts

Application February 8, 1939, Serial No. 255,298

3 Claims. (Cl. 51—117)

The invention relates to lapping machines, and more particularly to a micro-lapping machine for producing an accurate surface of high quality on either a cylindrical or flat work piece.

One object of the invention is to provide a simple and thoroughly practical lapping machine for producing fine finishes on work pieces. Another object of the invention is to provide an improved lapping machine in which either flat or cylindrical work pieces are lapped between a pair of opposed relatively rotatable lapping elements. A further object of the invention is to provide an improved lapping machine having a pair of opposed relatively rotatable lapping elements which are relatively revolved to produce a combined rotary and planetary movement of the lapping element relative to the work piece. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention:

Fig. 1 is a vertical sectional view through a micro-lapping machine embodying this invention;

Fig. 2 is a fragmentary plan view of the machine shown in Fig. 1, showing the driving mechanism for the upper lapping element;

Fig. 3 is a fragmentary sectional view taken approximately on the line 3—3 of Fig. 1, showing the arrangement of the work supporting cage;

Fig. 4 is a plan view of the work cage shown in Fig. 3;

Fig. 5 is a modified type of work cage for use in the lapping of flat work pieces;

Fig. 6 is a modified type of cage adapted for supporting cylindrical work;

Fig. 7 is a cross sectional view, showing the support for the cage construction shown in Figs. 5 and 6; and

Fig. 8 is a fragmentary sectional view of a modified drive for the upper lapping wheel.

The improved lapping machine as disclosed in the drawings comprises a base 10 which supports a pair of opposed spaced lapping elements or disks 11 and 12 which are provided with plane lapping surfaces arranged to engage opposite sides of a work piece to lap the same. The lap-

ping element 11 is mounted at the lower end of a vertically arranged rotatable spindle 13 which is rotatably journaled eccentrically within a rotatable sleeve 14. The spindle 13 and sleeve 14 are each provided with independent driving mechanisms so that the lapping element or wheel 11 may be rotated about the axis of the wheel spindle 13 and the sleeve 14 may be rotated about its axis of rotation to produce a planetary movement of the wheel spindle 13 and the lapping wheel or element 11.

Similarly, the lower lapping element or wheel 12 is supported on the upper end of a rotatable spindle 15 which is rotatably and eccentrically journaled within a rotatable sleeve or quill 16. The spindle 15 and sleeve or quill 16 are each arranged to be independently rotated so as to rotate the lapping element 12 about the axis of its supporting spindle and to move the lapping element in a planetary motion by rotating the sleeve or quill 16.

A driving mechanism is provided for rotating and revolving the lapping elements. A variable speed electric motor 20 is mounted within the base 10 of the machine. A pulley 21 mounted on the end of the motor drive shaft is connected by means of a belt 22 with a pulley 23 which is mounted on the outer end of a rotatable shaft 24. The shaft 24 is journaled in a bearing 25 in the base 10 of the machine. A bevel gear 26 is mounted on the inner end of the shaft 24 and meshes with a bevel gear 27 which is in turn keyed to a vertically arranged rotatable shaft 28. The shaft 28 is journaled within bearings 29 and 30 in the base 10.

The lower end of the shaft 28 is provided with a pulley 35 which is connected by means of a belt 36 with a larger diameter pulley 37 which is removably mounted on the lower end of the lap spindle 15 so as to rotate the lapping wheel 12. An idler pulley 38 is rotatably mounted on a stud 39 which is in turn supported by an idler bracket 40 to take up the slack and to properly tension the driving belt 36. The pulleys 35 and 37 may be readily changed to facilitate rotating the lapping element 12 at a desired speed.

The upper lapping element 11 is similarly rotated either in the same direction or in the opposite direction from the lower lapping element 12. As illustrated in Fig. 1, a driving mechanism has been shown for rotating the lap spindle 13 and the lap 11 in the opposite direction from the lap 12. A gear 45 is keyed on the shaft 28. The gear 45 meshes with a gear 46 which is keyed to a rotatable shaft 47 which is journaled in a

bearing 48 in the base 10. A pulley 49 is removably keyed onto the upper end of the shaft 47 and is connected by means of a driving belt 50 with a pulley 51 which is removably mounted on the upper end of the lap spindle 13 to rotate the spindle 13 and the upper lap 11 in a direction opposite to the rotation of the lower lap 12. An idler pulley 52 is rotatably supported on a shaft 53. The shaft 53 is supported by idler brackets 54 and 55 which are journaled on the upper portion of the rotatable shaft 28. The idler pulley 52 serves to take up the slack in the driving belt 50 and to tension the same so as to transmit the desired rotary motion to the upper lap 11.

If it is desired to rotate the spindle 13 and lap 11 in the same direction as the spindle 15 and lap 12, a pulley 49a (shown in Fig. 8) may be placed in position on the upper end of the shaft 28 between the idler brackets 54 and 55 and a belt connected between the pulley 49a and the spindle pulley 51.

In order to secure the desired and predetermined lapping action, it is desirable to impart a secondary motion to the lapping elements 11 and 12 in addition to their rotary motion. In the preferred construction, this movement is a planetary movement whereby the spindle 13 is revolved as it is rotated about the axis of the sleeve or quill 14, and similarly the spindle 15 is revolved as it rotates about the axis of the sleeve or quill 16. The vertical drive shaft 28 is provided with a driving gear 60 which is slidably keyed thereto and is held in adjusted position by means of a set screw 61. The gear 60 meshes with a gear 62 which is rotatably supported on a shaft 63. The shaft 63 is journaled in bearings 64 and 65 in a projecting portion of the base 10. The gear 62 meshes with a gear 65 which, as illustrated, is formed by cutting gear teeth in the peripheral surface of the sleeve or quill 14. The gear 65 is a wide faced gear having relatively wide gear teeth to facilitate longitudinal or axial movement of the quill 14. When the shaft 28 is rotated, it serves not only to transmit rotary motion through the belt 50 and pulley 51 to rotate the spindle 13 but also, through the gears 60, 62 and 65, to rotate the sleeve or quill 14 to impart a planetary movement to the lapping element 11 during rotation thereof.

Similarly, a gear 70 is mounted on the drive shaft 28. The gear 70 meshes with a gear 72 which is supported on a rotatable shaft 73. The shaft 73 is journaled in bearings 74 and 75 in the base 10. The gear 72 meshes with a gear 76 formed on the periphery of the sleeve 16. It will be readily apparent from the foregoing disclosure that when the shaft 28 is rotated, a rotary motion is transmitted by the belt 36 and pulley 37 to rotate the spindle 15 and the lapping element 11 about the axis of the spindle 15, and at the same time the gears 70, 72 and 76 serve to rotate the sleeve or quill 16 so as to impart a planetary motion to the wheel spindle 15 and lapping element 12 during rotation thereof.

As shown in Fig. 1 of the drawings, the quills 14 and 16 are timed and positioned so that the axes of the spindles 13 and 15, respectively, are in alignment with each other and travel in alignment during the rotary and planetary movement of the lapping elements 11 and 12. If desired, the quills 14 and 16 may be relatively adjusted so that the axes of the spindles 13 and 15 are out of alignment with each other during substantially the entire lapping operation. This

may be accomplished by loosening the set screw 61 and sliding the gear 60 out of mesh with the gear 66 and then rotating the quill 14 so that the axis of the spindle 13 is on the diametrically opposite side of the axis of the sleeve or quill 14. The gear 60 may then be moved upwardly into mesh with the gear 62 and locked in adjusted position by the set screw 61. This adjustment throws the axis of the spindle 13 out of alignment with the axis of the spindle 15 and maintains it in this out of line condition during the lapping operation when desired.

To facilitate loading of work pieces into the machine and also to produce the desired lapping engagement between the laps 11 and 12 relative to the work, it is desirable to provide means for producing a relative approaching and receding movement between the lapping elements 11 and 12. In the construction as illustrated in the drawings, the lapping element 11 is arranged for movement toward and from the lapping element 12. The sleeve or quill 14 is slidably mounted within the cylindrical aperture 11 of the base 10. Manually operable means is provided for producing a relative approaching and receding movement. This may comprise a manually operable spoked wheel 80 which is mounted on the outer end of a shaft 81 which is journaled in the base 10. The shaft 81 carries a gear 82 which meshes with circular rack teeth 83 formed in the periphery of the sleeve 14. By rotation of the wheel 80 in a clockwise direction (Fig. 1), the gear 82 acting upon the circular rack 83 will cause the quill 14 to move upwardly, thus separating the upper lap element 11. Similarly, the rotation of the wheel 80 in a counterclockwise direction serves to lower the quill 14 and the upper lap element 11 so that it approaches the lower lap 12 and may be moved into engagement with a plurality of work pieces located therebetween.

To facilitate rotation of the wheel spindle 13 during the vertical movement of the quill 14, the driving pulleys 49, 49a and the idler pulley 52 are preferably wide faced pulleys of a width at least equal to the maximum vertical movement of the quill 14, so that during this vertical positioning movement of the upper lap 11, the spindle 13 may be continuously driven by the belt 50.

A suitable work holding cage is provided for locating work pieces between the opposed plane faces of the lapping elements 11 and 12. As illustrated in Figs. 1, 3 and 4, a work cage 90 is provided having a plurality of non-radially extending work locating spindles 91 which serve to support a plurality of hollow cylindrical work pieces 92 thereon. A fixed guiding plate 94 is provided with a cylindrical aperture 95 slightly larger than the outer periphery of the spoked cage 90, 91, with the work pieces mounted thereon so that the cage and work pieces are free to move therewithin. The plate 94 is held in a fixed position by means of a plurality of spaced studs 96, 97, 98 and 99. These studs are screw threaded into a pan-shaped member 100 which is fixed relative to the base 10. A pair of nuts are provided on each of the studs 96, 97, 98 and 99, one located above and the other below the plate 94. These nuts serve as locating and holding means whereby the plate 94 may be raised or lowered to space it substantially midway between the opposed faces of the lapping wheels 11 and 12. This plate 94 is maintained in fixed relationship relative to the machine base and

the cage member 90 together with the work pieces 92 are placed in position within the aperture 95 and the lapping element 11 is moved downwardly into engagement with the work pieces 92 while the spindles and quills are rotated to produce a rotary and planetary movement of the lapping elements 11 and 12 so as to produce the desired and predetermined lapping operation on the work pieces 92. The work pieces, as illustrated in Figs. 1, 3 and 4, are hollow cylindrical work pieces.

This invention, however, is not limited to cylindrical type work pieces but is equally applicable to solid work pieces of a cylindrical shape as well as flat work pieces in which it is desired to lap opposed flat faces parallel to each other. Modified cage constructions have been illustrated in Figs. 5, 6 and 7. In Fig. 5 a cage 105 is provided with a plurality of apertures 106 which are arranged to receive circular work pieces 107 having flat opposed hollow surfaces to be lapped. This cage is applicable to any shape of flat work pieces and apertures are provided sufficiently large and preferably shaped as clearance holes slightly larger than the shape and size of the work pieces to be lapped.

A similar type work cage 110 has been illustrated in Fig. 6 for lapping solid cylindrical work pieces. The cage member 110 is provided with a plurality of non-radially arranged slots 111 which are slightly larger than the work pieces 112 to be lapped. Each of the cages 105 and 110 is provided with a peripheral flange 114 (Fig. 7) which is arranged to rest upon the upper surface of the fixed plate 94 so as to locate the cage 105 or 110 between the lapping elements 11 and 12.

The operation of this machine will be readily apparent from the foregoing disclosure. Assuming the various parts to have been previously adjusted and the speed of the motor 20 to have been adjusted by means of a rheostat (not shown) to produce the desired rotary speed to the drive shaft 28, and also assuming that the proper size of pulleys 35, 37, 49 and 51 have been mounted in position to produce the desired rotary speed to the lapping elements 11 and 12, the machine is then ready for a lapping operation. The lapping element 11 is in an upper or raised position and the work cage 90 having a plurality of work pieces 92 carried thereby is placed in position within the aperture 95 of the fixed guide plate 94. The motor 20 is then started to rotate the spindles 13 and 15 and to rotate the quills 14 and 16 so as to impart a rotary and planetary movement to the lapping elements 11 and 12. The upper lapping element is then moved downwardly by rotation of the manually operable wheel 80 to move the upper lapping element 11 into operative engagement with the work pieces 92. The weight of the upper lap may be positioned to produce the desired lapping action as the lapping elements.

11 and 12 are rotated and planetarily moved. If additional pressure is desired to increase the cutting action of the lapping wheels 11 and 12, a pressure device (not shown) may be utilized, such as that shown in my prior U. S. Patent No. 1,831,958 dated November 17, 1931.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a lapping machine having a base, opposed rotatable lapping elements supported thereby, means relatively to move said elements toward or from each other, driving means to rotate said elements about one axis, driving means simultaneously and positively to revolve said elements about an axis eccentrically disposed relative to the axis of rotation during rotation thereof, a freely rotatable work cage between said elements, and means including a fixed guide plate having a cylindrical aperture which surrounds said cage to prevent lateral movement thereof.

2. In a lapping machine having a base, opposed rotatable lapping elements supported thereby, means relatively to move said elements toward or from each other, means positively to rotate said elements about one axis, driving means simultaneously and positively to revolve said elements about an axis eccentrically disposed relative to the axis of rotation during rotation thereof, a freely rotatable work cage between said elements, means including a fixed guide plate having a cylindrical aperture which surrounds said cage to prevent lateral movement thereof, and means to adjust the position of said plate.

3. In a lapping machine having a base, opposed rotatable lapping elements and a rotatable work cage therebetween, means to move at least one of said elements relatively toward and from the other, a pair of rotatable spindles to support said elements, a pair of aligned rotatable sleeves rotatably supported in said base, eccentric bearing supports in said sleeve for said spindles, a drive shaft, means including a motor positively to rotate said shaft, driving connections between said shaft and each of said sleeves synchronously to rotate said sleeves, and driving connections between said shaft and each of said spindles synchronously to rotate said spindles.

HERBERT S. INDGE.
